(57) **CLAIM**

The ornamental design for a cleaning kit for mobile phone, as shown and described.

DESCRIPTION

FIG. 1 is a perspective view of a cleaning kit for mobile phone showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a bottom perspective view thereof; and,

FIG. 9 is a perspective view thereof, shown in an open state. The broken lines in the drawings depict portions of the cleaning kit for mobile phone that form no part of the claimed design.

1 Claim, 9 Drawing Sheets
